INVENTOR
Edward B. Nowosielski
BY
Albert D. Libby
ATTORNEY

UNITED STATES PATENT OFFICE.

EDWARD B. NOWOSIELSKI, OF BLOOMFIELD, NEW JERSEY, ASSIGNOR TO SPLITDORF ELECTRICAL COMPANY, OF NEWARK, NEW JERSEY.

MAGNETO CONSTRUCTION.

Application filed October 30, 1920. Serial No. 420,646.

To all whom it may concern:

Be it known that I, EDWARD B. NOWOSIELSKI, a citizen of the United States, residing at Bloomfield, in the county of Essex, State 5 of New Jersey, have invented certain new and useful Improvements in Magneto Constructions, of which the following is a description, reference being had to the accompanying drawings and to the figures of reference marked thereon.

My invention relates to magneto construction and has for its object a magneto of compact construction in which all available space is utilized so as to reduce the overall 15 length of the magneto.

Another object is to mount the commutator or distributor spool as far as possible from the bearings so as to prevent oil, dust, etc., from reaching the same.

Still another object of this invention is to 20 so place the distributor spool and brushes so as to be out of harm's way when opening the magneto for inspection or repairs.

Other objects will appear after reading 25 the specification and claims.

In the drawings which illustrate one embodiment of my invention—

Figure 1 is a view of the improved magneto with parts separated and the rotor 30 partially withdrawn.

Figure 2 is a medial section therethrough, the rotor being in place and

Figure 3 is a plan view of the underside of the base of my magneto.

My magneto is of the type disclosed in my 35 application Serial No. 365,305, filed March 12, 1920, and comprises a cast non-magnetic base 1 within which is embedded long laminated side pole pieces 2 and 3 and top pole 40 pieces 4 and 5 shown in Fig. 1, there being a space left between the top pole pieces. In engagement with the top pole pieces is a bridging laminated core piece 6 about which is wound the induction coil 7 having the

usual primary and secondary windings. To 45 retain the core 6 in place two straps 8 are provided which straddle shouldered portions 9 of the core piece and which are secured to the casting 1 by screws 10 or other suitable means. Positioned on the pole pieces 2 and 3 are the permanent magnets 11 and 12.

Within a bore 13 in the base there rotates 50 a rotor 14 having two sets of inductors 15 and 16, 17 and 18 respectively set at right angles to one another and separated by a

space medial of the rotor hitherto not utilized but within which according to the present invention is situated the distributor spool 20 of bakelite, americanite or the like having a commutator segment 19 embedded 60 therein. This distributor spool is about midway between the end bearings of the magneto.

In contact with the distributor spool there is a brush 21 spring pressed from a brush holder 22 inserted in between the pole pieces 4 and 5. The holder is maintained in place by means of two screws 23 passing through the base 1 and threaded into the holder as is clearly shown in Figs. 1 and 2. Within 70 a recess in said brush holder there abuts a secondary terminal 24, the other end of the secondary being grounded to the frame at any convenient point as to the core member 6.

Inserted through the bottom of the base and held in place by means of two screws 25 is the spark plug connecting block 26 carrying two brushes 27 inclined toward each other, each resiliently mounted within a conducting member 28 having a socket connection 29 adapted to receive a plug connector P which may be inserted through openings 30 in the base of the magneto. The base is also provided with two holes 31 to fit over 80 positioning pins on the magneto retaining support.

To enclose the magneto non-magnetic cover plates 32 and 33 are provided, spaced from the magnets by means of felt or other 90 gaskets 34 and 35, and mounted so as to clamp these cover plates to the base are the bearing and end plates 36 and 37 which are secured to the base by means of screws 38 which pass through the bearing plates and 95 cover plates and which are tapped into the base 1, shims 39 being interposed as is found necessary.

Upon the bearing plate 36 is mounted the breaker box 40 within which is mounted the 100 breaker mechanism, not shown, operated by the cam on the magneto shaft as is the common practice. A wire 41 connects one end of the primary to one of the contacts of the breaker mechanism, the other contact, the 105 breaker mechanism and the other end of the primary being conveniently grounded.

Having thus described my invention, what I claim is:

1. In a magneto construction a magneto 110

base, a rotor within the base, a distributer spool located on said rotor within the confines of the base and brushes mounted in the base in contact with the distributer spool.

5. 2. In a magneto, a magneto base, a rotor mounted within the base, said rotor having two sets of inductors, one set at each side of the medial line of the rotor, a distributer spool between the sets of inductors and 10 brushes situated within the base of the magneto engaging the distributer spool.

6. 3. In a magneto, a magneto base, pole pieces in said base, additional spaced apart pole pieces in said base, a brush and brush 15 holder in between the spaced apart poles, a rotor within the base, a distributer spool on said rotor in position to be engaged with

the brush, and additional brushes inserted through the base of the magneto in engagement with the distributer spool.

20

4. In a magneto construction, an interiorly located distributor spool, an interiorly located brush mounted in a block situated within the base of the magneto and in contact with said distributer spool, an electrical 25 connection for said brush terminating in a pin and socket connector, said connector extending laterally from said block, and openings in said base aligned with the connector in the block to enable the connection 30 of a conducting wire with the pin and socket connector.

25

In testimony whereof, I affix my signature.
EDWARD B. NOWOSIELSKI.
